CLAIM

The ornamental design for a receptacle head for power extension cord, substantially as shown and described.

DESCRIPTION

FIG. 1 is a left rear lower perspective view of an embodiment of a receptacle head for power extension cord depicted with receptacle covers and gate in closed positions; FIG. 2 is a right front upper perspective view thereof; FIG. 3 is a front elevation view thereof; FIG. 4 is a rear elevation view thereof; FIG. 5 is a right elevation view thereof; FIG. 6 is a left elevation view thereof; FIG. 7 is an upper plan view thereof; FIG. 8 is a lower plan view thereof; FIG. 9 is a right elevation view of the embodiment of a receptacle head for power extension cord depicted with receptacle covers and gate in open positions; FIG. 10 is a front elevation view thereof; FIG. 11 is a rear elevation view thereof; FIG. 12 is a right front upper perspective view thereof; and, FIG. 13 is a left rear upper perspective view thereof. The broken lines in the drawings are for the purpose of illustrating portions of the receptacle head for power extension cord that form no part of the claimed design.

1 Claim, 5 Drawing Sheets
